UNITED STATES PATENT OFFICE.

WILLIAM O. WEBBER, OF BOSTON, MASSACHUSETTS, ASSIGNOR TO WALTER C. CARR, OF NEW YORK, N. Y.

APPARATUS FOR PREHEATING AND MOISTENING COMPRESSED AIR.

SPECIFICATION forming part of Letters Patent No. 681,357, dated August 27, 1901.

Application filed August 29, 1900. Serial No. 28,483. (No model.)

To all whom it may concern:

Be it known that I, WILLIAM OLIVER WEBBER, of the city of Boston, county of Suffolk, and State of Massachusetts, have invented 5 certain new and useful Improvements in Apparatus for the Preheating and Moistening of Compressed Air; and I hereby declare that the following is a clear, full, and exact description of the same.

10 This invention relates to an improved form of apparatus for the preheating and moistening of compressed air before being used in air engines or motors, and has for its object the combination of a self-feeding furnace and 15 a system of heating-pipes and deflectors which may be added to indefinitely, so as to increase the capacity of the heaters, also so arranged as to heat the air progressively, and also at the same time and progressively as 20 the heating of the air is accomplished means for the introduction of moisture in finely-divided particles into the compressed air, so as to moisten the air at the same time that it is heated.

25 In the accompanying drawings, Figure 1 is a vertical section of a single-series heater on the lines 1 1 on Fig. 2. Fig. 2 is a sectional plan of the same heater on line 3 3, Fig. 1. Fig. 3 is a sectional elevation of the heater 30 on the line 2 2, Fig. 2. Fig. 4 is a sectional plan of a two-series two-progressive heater. Fig. 5 is a part-vertical section on the line 4 4, Fig. 4, through the fire-pot a' , surrounding pipes g' , and sectional covering.

35 The same letters apply to the same parts in each view.

A is the base-burning heater, consisting of a fire-brick-lined furnace a' , grate a^2 , ash-pit a^3 , and fuel-tube a^4 , extending downward 40 from the top of the furnace and axially centered with relation to the furnace a' . This fuel-fed tube is provided with a removable cover a^5 . This heater is provided with a vertical opening a^6 , at the rearward part thereof, 45 through which the hot gases of combustion pass into the heat-absorption chamber B, which consists of a series of vertical diaphragms b b' b^2 b^3 b^4 b^5 b^6 , having openings through them alternately at top and bottom 50 and being arranged in alternate, so that heat passing over the top of the first diaphragm

must pass under the bottom of the second, over the top of the third, and alternately so on, the entrance-opening being at the top of the first diaphragm and the escape-opening 55 being at the top of the last diaphragm, where connection is had with the chimney-support C. This heat-absorption chamber is situated on the top of a two-part header D, which also serves to act as an air-moistening chamber. 60 The two passages d' and d^2 of the two-part header D are connected by means of vertical return-bends of pipe d^3 and d^4 , which may be built of ordinary pipe and fittings or may be bent inverted-U-shaped tubes. These vertical bends of pipe project upwardly into the heat-absorption chamber B, so as to be in about mid-position between the vertical deflector-plates b , b' , b^2 , b^3 , b^4 , b^5 , and b^6 . Through the bottom of the inlet-chamber of the two-part header D project moistening-nozzles E, provided with spray-tips e , and these moistening-nozzles E are connected by suitable fittings to a supply of water under pressure. These nozzles are so arranged as to be in 75 the center of the vertical axis of the inlet-leg of the vertical inverted-U-shaped tubes d^3 and d^4 , and the top of the vertically-extending spray-tips e are located below the opening into the inlet-legs of the inverted-U-shaped tubes d^3 and d^4 , so as to obtain an 80 ejector action in accelerating the passage of the air through these tubes.

The action of this apparatus is as follows: A fire being started on the grate a^2 and in 85 the furnace a' of the heater A and the tube a^4 being filled with coke or anthracite coal, the hot gases of combustion rising from the burning fuel between the top of the furnace a' and the bottom of the fuel-tube a^4 passes 90 to the top of the chamber surrounding the tube a^4 , through the opening a^6 , over the top of the vertical diaphragm b , down between this diaphragm and its alternate diaphragm b' , under whose bottom it passes, then upward between b' and b^2 , over the top of b^2 , and so on alternately up and down, beneath, and over and between the succeeding alternate diaphragms until it finally escapes through the chimney connection C at the top of the 95 last section. At the same time that this combustion is taking place compressed air is be- 100

ing let into the inlet-chamber d' of the two-part header D by any suitable pipe connection at the end farthest from the furnace, and at the same time water, under a slightly 5 greater pressure than that of the air, is being let in through the nozzles E and spray-tips e. The combined action of the air under its own pressure and the jet of moisture causes the air to rise very rapidly in the legs of the U-shaped tubes d^3 and d^4 , &c., and pass over and down into the outlet-section d^2 of this header. As the compressed air, therefore, is forced up through the inverted-U-shaped tubes it is thoroughly impregnated with moisture 10 and at the same time brought into contact with the heat passing alternately downward and upward around the outside of these tubes and in this way absorbs moisture and heat during its passage through these tubes.

20 In the diagram, Fig. 4, of a four-section two-series heater the air after entering the air-inlets d^5 in the first set of headers D and D' passes upward through the inverted-U-shaped tubes, as described above, and is partially 25 heated and at the same time partially moistened by a supply of water entering through the pipe G. The air thus partially heated and moistened passes onward from the header D, through the pipe d^7 , into the header D², and the air after passing through the header D' passes through the pipe d^8 into the header D³ and after passing through these headers escapes through the outlet-pipes d^9 d^{10} d^{11} . During this passage through 30 the second set of headers D² and D³ and their connecting pipes, which are situated nearer the furnace than the set first described, the air is further heated and at the same time further moistened by a supply of water passing 35 through the supply-pipe G', which is coiled around the outside of the fire-pot A', and thus heated before passing through the spray-nozzles e into the second series of headers D² D³.

40 The whole of this heating apparatus is surrounded by an air-space H and non-conducting covering I, with the exception of the ash-door, cover to the fuel-tube, and connection to the chimney, so as to prevent radiation of 45 heat and cause the heater to be as efficient as possible.

I am well aware that preheaters for raising the temperature of compressed air have been used for some time; also that the idea 50 of preheating air before using it in motors is old; also that the idea of moistening air for use in motors is old; but

What I desire to claim and secure by Letters Patent of the United States is as follows:

60 1. In an apparatus for the progressive moistening and heating of compressed air, the combination with a compressed-air passage, of a furnace having a series of chambers adapted to be heated at different temperatures, air-circulating pipes extending through 65 said chambers, and a moistening apparatus operatively arranged to discharge into each

of said circulating-pipes, substantially as described.

2. In an apparatus for the progressive 70 moistening and heating of compressed air, the combination with a compressed-air passage, of a furnace having a series of chambers arranged at successive points nearer to said furnace, air-circulating pipes extending 75 through said chambers, and a moistening apparatus consisting of a series of discharge-nozzles, each of which opens into a circulating-pipe, substantially as described.

3. In an apparatus for the progressive 80 moistening and heating of compressed air, the combination with a compressed-air passage, of a furnace having a series of heating-chambers arranged at successive points nearer to said furnace, air-circulating pipes extending 85 through said chambers, and a moistening apparatus consisting of discharge-nozzles, each of which opens into a circulating-pipe and are arranged in series at successive points nearer to the furnace, substantially as de- 90 scribed.

4. In an apparatus for the progressive moistening and heating of compressed air, the combination with a compressed-air passage, of a furnace having a series of heating-chambers composed of sections progressively arranged at successive points nearer said furnace and operatively connected alternately at their top and bottom, air-circulating pipes in each of said chambers, and a moistening 100 apparatus consisting of a series of discharge-nozzles arranged relative to said pipes at successive points nearer to the furnace, substantially as described.

5. In an apparatus for the progressive 105 moistening and heating of compressed air, the combination with a compressed-air passage, of a furnace, of a series of heating-chambers operatively connected thereto, consisting of air-chambers connected by circulation-tubes interposed between diaphragms extended alternately in opposite directions and a moistening apparatus operatively arranged to discharge into each of said chambers, substantially as described. 115

6. In an apparatus for the progressive moistening and heating of compressed air, the combination with a compressed-air passage, of a furnace having a series of heating-chambers operatively connected thereto, consisting of sectional air-chambers connected by circulation-tubes operatively connecting the inlet and outlet sections of the air-chambers, and a moistening apparatus operatively arranged to discharge into each of said chambers, substantially as described. 125

7. In an apparatus for the progressive moistening and heating of compressed air, the combination with a compressed-air passage, of a furnace having a series of heating-chambers, operatively connected thereto, consisting of air-chambers connected by circulation-tubes, and a moistening apparatus consisting of spray-nozzles operatively arranged 130

to discharge into each of said chambers, and operatively connected to a supply-conduit passing through the furnace, substantially as described.

- 5 8. In an apparatus for the progressive moistening and heating of compressed air, the combination with a compressed-air passage, of a furnace having a series of heating-chambers connected thereto, consisting of a
10 plurality of sectional air-chambers connected by tubes operatively connecting the inlet and outlet sections of the air-chambers, and a

moistening apparatus consisting of spray-nozzles, operatively connected to discharge into the inlet side of each of said chambers, 15 substantially as described.

In testimony whereof I have hereunto affixed my signature in the presence of two subscribing witnesses.

WILLIAM O. WEBBER.
